Application February 29, 1936, Serial No. 66,330

1 Claim. (Cl. 220—67)

Our invention relates to containers, particularly to containers made of sheet metal.

It has been known for years that the bodies of nail kegs, oil drums, large paint cans, and the like, may be constructed of sheet metal, and it has been realized that certain advantages may be gained by using wooden heads in the sheet-metal bodies of such containers. So far as we are aware, however, none of the hitherto proposed wood-and-metal containers has enjoyed wide commercial success. In many of the proposed structures the wooden heads are not adequately secured in assembly with the sheet metal bodies; in others, in which security and rigidity of assembly are present, the heads are not sealed in assembly, in such manner as to provide a liquid proof container; and in those containers which avoid these objections, we find such elaborations in structure as to make the cost of production and the labor of installation too great for practical purposes.

Our invention consists in specific refinements in structure, by virtue of which a wooden head may be rigidly secured and adequately sealed in assembly with the sheet metal body of a container. We dispense with special fastening means, and avoid the use of specialized multiple-piece heads, to the end that simplicity and economy may be obtained in largest measure.

30 In the accompanying drawing the invention is shown, by way of illustration and not limitation, as it is embodied in a nail keg. Fig. I shows the keg in side elevation, and Fig. II shows it in end elevation; Fig. III is a fragmentary view of the keg in axial section, and to larger scale, and illustrating the head in course of assembly with the body; Fig. IV is a similar view, showing the assembly completed; Fig. V is a fragmentary sectional view, showing the completed assembly of
35 Fig. IV to still larger scale; and Figs. VI and VII are views comparable with Fig. V, severally illustrating modifications in detail.

Turning to the drawing, our keg includes a cylindrical body 1 of sheet metal, say a single rectangular piece of sheet steel, curled into cylindrical form and welded in known way along its overlapped edges 1a. Two or more circumferential ribs 2 are pressed in the sheet metal body of the cylindrical shell. Such ribs strengthen the shell, and facilitate the rolling of the finished keg upon its side.

One end of the keg may be provided in usual way with a sheet metal head, and the opposite end with a head of compressible material in accordance with our invention. In this case both

ends of the keg are provided with heads of compressible material, and advantageously circular discs 3 of compressible wood are used.

Adjacent each end of the body 1, a circumferentially extending groove or croze 4 is formed in the sheet metal, providing within such body a seat 5. Through each open end of the body a head 3 is introduced, Fig. III, and positioned in peripheral engagement with the seat 5. Then the adjacent circular edge of the sheet metal cylinder is rolled downward, providing a chime 6 that peripherally overlies the head 3 and serves to hold the head to its seat. While the invention is found in structure of this general nature, it will be understood that our inventive contribution lies in specific refinements.

In accordance with the invention, we so shape the outwardly open groove or croze 4 in cross-section that the seat or face 5 is inclined or chamfered in the area engaged peripherally by the wooden head 3, and the direction of inclination of the seat 5 is downward and inward with respect to the adjacent peripheral edge of the cylindrical shell. In still further refinement, the head 3 is peripherally bevelled or chamfered, forming an inclined face as indicated at 3a in Fig. III, whereby the head is adapted to seat snugly upon the inclined seat, as shown in Fig. IV. Then, by means of instrumentalities with which this invention is not immediately concerned, we not only roll or coil the peripheral edge of the sheet metal cylinder inward, into the form of the peripheral chime or head 6, but additionally, in

peripheral chime or bead 6, but additionally, in forming such chime or bead, we force the under-turned edge of the sheet metal into the peripheral body material of the head, as indicated at 7 in Fig. V. That is to say, the compressible peripheral edge of the head 3 is subjected to substantial compressive stress, thereby forcing the chamfered periphery of the head with wedging effect against the inclined seat 5. Manifestly, the peripheral wedging of the head 3 against the seat 5 is such in nature as to tend radially to expand the seat and the adjacent wall of the cylinder 1, thereby subjecting such seat and wall to tension in a circumferential direction, with the consequence and effect that the usual wrinkles and irregularities found in die-pressed sheet metal seats are entirely removed, or are caused to conform to the periphery of the head. Within the inner and outer flat faces of the head, the peripheral edge of the head is compressed between the chime and the inclined seat, and this compression, by virtue of the wedging effect already described, insures (throughout the periph- 55

ery of the head) a snug surface-to-surface engagement with the walls of the cylinder 1, and provides the desired liquid tight and rigidly secure integration of the parts. Such structure has been found effective to exclude atmospheric moisture from the interior of the container, and, manifestly, such characteristic is particularly valuable in the case of nail kegs and the like.

While the use of a resilient or compressible gasket or a ring of rigid material, between the head and the seat (or between the chime and the head) is within contemplation of the invention it will be understood that, by virtue of the structure described, such use of gaskets or the like is, advantageously, avoided.

In Fig. VI we illustrate that the periphery of the head 3 may be chamfered at 3b, as well as at 3a, whereby the head-compressing chime 6 is effective upon the chamfer 3b rather than on the flat, outer face of the head. In further modification the chime 6 may be formed by first pressing the sheet metal inward against the chamfer 3b and then rolling the outer edge of the metal outward and downward, as indicated in Fig. VII. In such case the compressive stress is exerted upon the wood by the inner portion 8 of the chime. And in still further modification

and refinement, a circumferential rib or ridge 9 (Fig. VI) may be formed in or comprise the seat against which the periphery of the head is compressed. The rib "bites" into the compressible periphery of the head and further cooperates to the ends in view.

We claim as our invention:

A container comprising a sheet of metal formed into an open-ended cylinder united along its meeting or overlapping edges, and a head secured in an end of said cylinder, said head consisting in a discular member formed of compressible wood, and the wall of said cylinder including adjacent said end of the cylinder an inwardly projecting circumferential groove, with the sheet metal in which the groove is formed providing an inwardly and downwardly inclined circumferential face within the cylinder, said head having a peripheral, inwardly and downwardly inclined face which engages said first face, and the adjacent edge of said cylinder being coiled into a circumferential chime peripherally compressing said head and tightly pressing said inclined face of the head against said first face.
